FIG. 1.

FIG. 2.

FIG. 3.

FIG. 4.

FIG. 5.

FIG. 7.

Inventor

Charles M. Denison,
By his Attorneys

Edgar Hale & Co.

UNITED STATES PATENT OFFICE.

CHARLES M. DENISON, OF EAST ORANGE, NEW JERSEY.

CINDER-GUARD.

1,333,063.

Specification of Letters Patent.

Patented Mar. 9, 1920.

Application filed March 5, 1919. Serial No. 280,685.

To all whom it may concern:

Be it known that I, CHARLES M. DENISON, a citizen of the United States, and residing at East Orange, in the county of Essex and 5 State of New Jersey, have invented certain new and useful Improvements in Cinder-Guards, of which the following is a specification, such as will enable those skilled in the art to which it appertains to make and 10 use the same.

This invention relates to cinder guards and particularly to devices of this class designed for use in connection with the windows and window frames of passenger cars; 15 and the object of the invention is to provide a foldable or collapsible device of the class specified which is normally held in a closed or inoperative position and adapted to be moved into an extended or operative position by hand; a further object being to provide a device of the class specified which is automatically closed in the operation of closing a window of a car; and with these and other objects in view the invention consists in a device of the class and for the purpose specified which is simple in construction and operation and efficient in use. 25

The invention is fully disclosed in the following specification, of which the accompanying drawing forms a part, in which the separate parts of my improvement are designated by suitable reference characters in each of the views, and in which:—

Figure 1 is a central vertical section 35 through a part of a window frame of a passenger car and showing my improved cinder guard attached thereto in its normal position;

Fig. 2 is a view similar to Fig. 1 with 40 parts of the construction in a different position;

Fig. 3 a partial section on the line 3—3 of Fig. 2;

Fig. 4 a partial section on the line 4—4 of 45 Fig. 2 on an enlarged scale;

Fig. 5 a partial section on the line 5—5 of Fig. 1 and on an enlarged scale;

Fig. 6 a partial section on the line 6—6 of Fig. 4 and on an enlarged scale; and,

50 Fig. 7 a partial section on the line 7—7 of Fig. 2 and on an enlarged scale.

In Figs. 1 and 2 of the drawing, I have indicated at 10 a part of a passenger car, and at 11 one of the window frames of said car. Mounted in and movable vertically in

the window frame 11 are upper and lower sashes 12 and 13. The above described construction may be similar to that usually employed in railway passenger cars and is shown diagrammatically to illustrate the 60 method of attaching one of my improved cinder guards 14 in connection with a window frame.

My improved cinder guard comprises an elongated casing 15, composed of a back 65 member 16 and a front and side member 17 which is L-shaped in form in cross section, as clearly shown in Figs. 4, 5 and 7. The front and side member 17 are connected with the upper and lower end portions of the back member 16 as shown at 18 by welding, brazing or otherwise, and the attached portions of said parts are provided with screw holes 19 through which screws or similar attaching devices 20 are adapted to pass in securing the casing 15 to one side of the window frame 11 in the manner shown in Figs. 1 and 2 of the drawing. The connection of the front and side member 17 with the back member 16 to form a casing 15 produces a 80 chamber 21 in the casing which opens outwardly through one side thereof as shown at 22 in Figs. 4 and 5 of the drawing.

In practice, I pivot to the bottom portion of the front of the casing 15 and as shown 85 at 23 an arm 24 which is provided with a plurality of offset portions 25 as clearly shown in Figs. 2 and 4 of the drawing, and a similar arm 26 is pivoted to the back of the casing 15 as shown at 27, and adjacent 90 to the upper end of said casing and is also provided with a plurality of offset portions 28. Pivoted to the offset portions 25 and 28 of the arms 24 and 26 as shown at 29 and 30 respectively, are shutter members 31, 32 and 95 33. The shutter members 31 and 33 are provided with inwardly directed flanges 34 and 35 at one side edge thereof, while the central shutter member 32 is provided with oppositely directed flanges 36 and 37 on 100 both edge portions thereof, and these flanges coöperate with the flanges 34 and 35 on the shutter members 31 and 33 respectively, to hold said members intact to prevent the separation thereof, as well as serving to 105 produce a tight connection between the separate shutter members when in their extended position as shown in Figs. 2, 4 and 7 of the drawing.

A lever 38 is pivoted centrally or is ro- 110

tatably mounted in the lower end portion of the front wall casing 15 as shown at 39 and one end 40 of which extends into the casing and is pivoted centrally of the outer shutter member 31 as shown at 41 and the other end 42 of the lever extends outwardly of the casing 15 and serves as a handle or operating arm for the lever, and by means of which the shutter members 31—33 may be moved by hand into the position shown in Figs. 2, 4 and 7, and automatically returned into their closed or normal position as shown in Figs. 1 and 5, and as hereinafter described.

15 A coil spring 43 is mounted in the casing 15 and one end of said spring is attached to the side of the casing as shown at 44 and the other end of which is connected to the pivoted end of the lever 38, or the end portion 40 of said lever as shown at 45, and this spring serves to hold the shutter members 31—33 normally in their closed or inoperative position as is indicated in dotted lines in Fig. 6 and will also serve to hold said shutter members in their open or extended position as shown in Figs. 2, 4 and 7, and as is indicated in full lines in Fig. 6. The spring 43 in addition to its foregoing functions also aids to automatically close the shutters as hereinafter set out.

From the foregoing description the operation of my improved device will be readily understood when taken in connection with the accompanying drawing and the following statement. When the guard 14 is in its normal position, the shutter members 31 and 33 are normally contained within the casing 15 as is illustrated in Figs. 1 and 5, and the lower sash 13 in the window frame 11 is closed. When the lower sash 13 is opened as shown in Fig. 2 and it is desired to use the cinder guard 14, the shutter members 31—33 are moved into the position shown in Fig. 2 by raising the end portion 42 of the lever 38 from the position shown in Fig. 1 to that shown in Fig. 2, which operation extends said shutter members by reason of the pivotal connection of the other end portion 40 of said lever with said shutter members, and in this position of the parts said shutter members are held against upward movement by the spring 43 which tends to hold the shutter members in their extended positions.

55 When it is desired to close the sash 13, the downward movement of said sash will strike the end portion 42 of the lever 38 and move said end portion downwardly, which operation moves or starts to move the shutter members inwardly into the casing, and in this operation and after the sash 13 has been closed or moved into the position shown in Fig. 1, the spring 43 will operate to complete the closing of the shutter members or their movement into the casing 15

and said spring will hold said shutter members within the casing until they are moved out into their extended position by hand.

It will be understood that while I have shown certain details of construction for carrying my invention into effect, it will be apparent that I am not limited to these details, and various changes in and modifications of the construction herein shown and described may be made, within the scope of the appended claims, without departing from the spirit of my invention, or sacrificing its advantages.

Having fully described my invention, what I claim as new and desire to secure by Letters Patent, is:

1. A device of the class described comprising a casing open at one side, a plurality of shutter members movably mounted in said casing and adapted to be extended through the open side thereof and withdrawn thereinto, means mounted in said casing and adapted to operate said shutter members, and tensional means mounted in said casing and operating in connection with said first named means.

2. A device of the class described comprising an elongated box-shaped casing, a plurality of shutter members movably mounted in said casing and adapted to be extended therefrom and withdrawn thereinto, a lever rotatably mounted in the casing, one end of said lever being connected with and adapted to operate said shutter members and the other end of said lever serving as an operating arm, and tensional devices mounted in the casing and adapted to operate in connection with said lever to hold said shutter members in their closed and extended positions.

3. A device of the class described comprising a casing, a plurality of shutter supports pivoted to said casing, shutter members pivotally connected with said supports, a lever rotatably mounted in the casing, one end of said lever being connected with one of said shutter members and the other end of said lever serving as an operating arm to move the shutter members and their supports into different positions, and a tensional device for holding said shutter members and their supports in their collapsed and extended positions.

4. A device of the class described comprising an elongated box-shaped casing opening outwardly through one side thereof, arms pivoted to the top and bottom portions of the casing, shutter members pivotally connected to said arms, a lever rotatably mounted in the casing, one end of said lever passing into the casing and being pivoted to one of said shutter members, the other end of said lever extending outwardly through the casing and serving as an operating arm to move the shutter members and

5 said arms into different positions, and a spring secured to the casing and to the central portion of said lever and adapted to hold the shutter members and said arms in their operative and inoperative positions.

10 5. A device of the class described comprising an elongated box-shaped casing opening outwardly through one side thereof, arms pivoted to the top and bottom portions of the casing, said arms being each provided with a plurality of offset portions, shutter members pivotally connected to the offset portions of said arms, the adjacent edges of said shutter members being overlapped and interlocked, a lever rotatably mounted in the casing, one end of which is pivoted to one of said shutter members and the other end of which serves as an operating arm to move the shutter members, and said arms 15 into different positions, a spring secured to the casing and to the central portion of said lever and adapted to hold the shutter members and said arms in their operative and inoperative positions.

20 25 6. A guard device of the class described comprising two pivoted arms, a plurality of shutter members pivotally connected with each of said arms, a stationary support and a lever rotatably mounted in said support,

30 one end of said lever being connected with one of said shutter members and the other end of said lever serving as an operating arm to move the shutter members and said arms into their collapsed and extended positions.

35

7. A guard device of the class described comprising two pivoted arms, said arms being each provided with a plurality of offset portions, shutter members pivotally connected to the offset portions of said arms, a 40 stationary support, a lever rotatably mounted in said support, one end of said lever being pivoted to one of said shutter members and the other end of which serves as an operating arm to move the shutter members 45 and said arms into different positions, and a spring connected with said lever and adapted to hold the shutter members and said arms in their operative and inoperative positions.

50

In testimony that I claim the foregoing as my invention I have signed my name, in presence of the subscribing witnesses, this 3rd day of March, 1919.

CHARLES M. DENISON.
